UNITED STATES PATENT OFFICE.

WILLIAM ALFRED NICKLESS, OF NEW YORK, N. Y., ASSIGNOR TO A. STEINHARDT & BRO., OF NEW YORK, N. Y.

VENTILATING SHOE OR SLIPPER TREE.

1,095,917.

Specification of Letters Patent.

Patented May 5, 1914.

Application filed November 29, 1913. Serial No. 803,684.

To all whom it may concern:

Be it known that I, WILLIAM A. NICKLESS, a citizen of the United States, and a resident of the city of New York, borough of Brooklyn, in the county of Kings and State of New York, have invented a new and Improved Ventilating Shoe or Slipper Tree, of which the following is a full, clear, and exact description.

10 The invention relates to shoe forms held in place in a shoe or slipper by the use of a straining rod or a spring.

15 The object of the invention is to provide a new and improved ventilating shoe or slipper tree arranged to insure proper stretching of the shoe or slipper and to permit air to circulate in both a longitudinal and a vertical direction thus preventing undue shrinking of the shoe material and restoring and 20 preserving the shape of the shoe or slipper.

25 In order to produce the desired result use is made of a toe or a vamp form having longitudinal passages beginning at the back of the form and extending forwardly, and vertical passages intersecting the said longitudinal passages and extending from the bottom of the form to the arched top thereof.

30 A practical embodiment of the invention is represented in the accompanying drawings forming a part of this specification, in which similar characters of reference indicate corresponding parts in all the views.

35 Figure 1 is a side elevation of the tree as applied to a shoe, the latter being shown in section; Fig. 2 is an enlarged plan view of the tree; Fig. 3 is a sectional side elevation of the same on the line 3—3 of Fig. 2; Fig. 4 is a cross section of the same on the line 40 4—4 of Fig. 3; Fig. 5 is a plan view of a tree provided with longitudinal passages of modified form; and Fig. 6 is a sectional side elevation of the same on the line 6—6 of Fig. 5.

45 The toe or vamp form A of the ventilating shoe or slipper tree is preferably made of hard wood and is provided with a flat bottom, an arched top and a straight back, as plainly indicated in the drawings. The back 50 of the form A is secured to one end of a straining rod or flat spring B provided at its other end with a heel piece C, preferably in the form of a ball adapted to rest against the back of the shoe at the heel, as plainly

indicated in Fig. 1. The form A is provided with a series of longitudinally extending passages E beginning at the back of the form and extending forward therein a desired distance, as indicated in Figs. 2 and 3. The longitudinal passages A are intersected by vertical passages F extending from the flat bottom of the form to the arched top thereof, so that air can readily circulate through these said passages E and F.

45 As shown in Figs. 5 and 6, the longitudinal passages E' extend from the back of the form A clear through to the arched top thereof, and the vertical passages F' intersect the said longitudinal passages E', the same as above described in reference to the 50 passages F and E.

55 It will be noticed that when the tree is in position in the shoe or slipper D, as shown in Fig. 1, then the straining rod or spring B is curved and exerts a forward pressure 60 on the form A so as to push the same forwardly and firmly in contact with the fore part of the shoe or slipper D. It will also be noticed that the sole as well as the vamp 65 of the shoe or slipper is ventilated owing to the vertical passages F intersecting with the longitudinal passages E, and consequently the shoe material is not liable to shrink but is kept in proper condition. It 70 will further be noticed that by the arrangement described in reference to the shape of the shoe or slipper is restored and preserved.

75 Although I have described the form as made of wood it is evident that the same may be made of other suitable material.

80 Having thus described my invention, I claim as new and desire to secure by Letters Patent:

85 1. A ventilating shoe or slipper tree, comprising a spring having a spherical heel piece 90 and a toe form attached to one end of the said spring, the said form consisting of a solid wooden body having a series of longitudinally-extending passages and vertical 95 passages intersecting the said longitudinal 100 passages and extending from the bottom of the form to the upper surface thereof.

105 2. A ventilating shoe or slipper tree, comprising a spring and a toe form attached to one end of the said spring, the said form consisting of a solid wooden body having a series of longitudinally-extending passages 110 extending from the back of the form in a

forward direction out through the upper surface of the body and vertical passages intersecting the said longitudinal passages intermediate the ends thereof and extending from 5 the bottom of the body to the upper surface of the same.
In testimony whereof I have signed my

name to this specification in the presence of two subscribing witnesses.

WILLIAM ALFRED NICKLESS.
